UNITED STATES PATENT OFFICE

2,370,761

VALVE TAPPET CONSTRUCTION

Harry E. Voorhies, Grosse Pointe Woods, Mich.,
assignor to Eaton Manufacturing Company,
Cleveland, Ohio, a corporation of Ohio

Application June 28, 1943, Serial No. 492,503

13 Claims. (Cl. 123—90)

This invention relates to automatic compensating tappets for operating valves of internal combustion engines, and more especially, concerns improvements in the construction and arrangement of compensating mechanism for tappets of such character.

One object of the present invention is the provision of an improved and simplified construction for such tappets and specifically to provide a separate cylinder member therefor for receiving a reciprocable plunger and associated valving means, which may be manufactured separately and applied as a unit to the tappet body.

The type of tappet to which this invention relates may comprise a mushroom-shaped device having an enlarged head which contacts the cam, and a tubular body which extends therefrom having an inner portion which is arranged to contact with the valve stem; or a so-called barrel-shaped body which has a body of uniform diameter and functions in a similar manner. It is usual to provide such a tappet with a bore which forms a reservoir or well to contain oil or other hydraulic operating medium, and to fit a reciprocable plunger in the upper end of the bore, to provide a spring or other resilient means to urge the plunger outwardly of the bore and against the valve stem, and to provide a valve controlled trap in which oil or other hydraulic medium is inducted upon the outward movement of the plunger to provide a hydraulic column against which the end of the plunger will bear when it is forced downwardly in the tappet body. A construction such as described is more fully illustrated in the Voorhies Patent No. 2,074,034, issued March 16, 1937, for Tappet construction.

The present invention proposes to advance the state of this art further by elimination of the substantially blind plunger pocket in the separate cylinder. Accordingly, to this end, the separate cylinder unit of the self-compensating mechanism which is inserted in the tappet body is made of two or more pieces for simplification of manufacture, and this has resulted in improved operating and inspection characteristics.

Further and other objects of the present invention reside in the novel combination and arrangement of parts about to be described, when considered in conjunction with the drawing forming a part of this specification, and which are more particularly pointed out in the appended claims.

In the drawing like reference characters denote corresponding parts in the several views, and in which:

Fig. 1 is a longitudinal cross-sectional view of a tappet embodying this invention, shown positioned between a valve stem and cam; and,

5 Figs. 2, 3, 4, 5, and 6 are views generally similar to Fig. 1 of the separate cylinder removed from the tappet body, but illustrating other modified forms of tappets constructed according to the principles of this invention.

Now having reference to drawing, particularly 10 to Fig. 1, the end of the stem of a conventional poppet valve is designated 1 and which is urged downwardly to its seat by a spring (not shown) in a well known conventional manner. A conventional cam shaft 2 has the usual cam 3 thereon and is arranged to move the tappet upwardly 15 in a tappet guide sleeve 4 provided in the cylinder block of the engine (not shown). The tappet body, generally designated 6, is of the conventional mushroom shape and provided with an enlarged cam-contacting head 7 and an elongated body 8. The body 8 has a stepped hollow bore, which provides a seat for the hydraulic compensating mechanism, to be described, and a lower closed end which serves as a reservoir for operating liquid which is supplied through the side of the guide 4 by a pipe means 10 connected with the usual lubricating system of the engine. Access to the reservoir 9 of the tappet body 8 from the pipe 10 is effected by means of a circumferential groove 11 and a hole 12 thereinto.

Inserted in the enlarged portion of the bore 8, on the step or seat 13, is an apertured valve-retaining or valve seat member 15 which seats and substantially seals a separate open-ended cylinder 16. For effecting a more complete seal of the juncture of the separate cylinder 16 and the valve-retaining member 15 a yieldable sealing means 17 may be used. The seal 17 is preferably Neoprene or other rubber-like material 40 which is radially and axially acted upon by pressure of the operating fluid trapped in the compression chamber and is flowable under the influence thereof to provide a fluid-tight seal, although it may be a metallic material such as lead 45 or babbitt which would be likewise affected. Various sealing means modifications are shown in subsequent views, to be described, wherein the seal may have an additional function to provide a combination seal and a portion of the valve seating surface. Slidably extended from the lower apertured end of the valve retaining member is a hollow tubular element 18 having, in this instance, a poppet valve portion 19 integrally formed on the upper end thereof arranged to be 50 angularly seated on a complementary portion of

the valve retaining member, and which, when the members 15, 18 are seated in the bore of the tappet body 8, extends below the oil inlet aperture 12 and well down into the oil reservoir 9 in the lower part of the tappet body. A snap ring 20 as shown, or any other suitable means, may be used to limit opening movement of the valve portion 19 to a predetermined amount as determined by operating characteristics.

Positioned in the separate open ended cylinder sleeve 16 is a piston plunger 21 which at its upper end contacts the end of the valve stem 1. In the case of an overhead valve engine it may contact the push rod, or other selected part of the operating mechanism of the valve train. Extended between the upper end of the plunger 21 and the separate cylinder 16 is a plunger spring 22 which biases the plunger outwardly of the cylinder and keeps it from settling on the head of the valve element 19. However, in the event of complete loss of operating liquid, the plunger 21 may reach the bottom of the separate cylinder and rest on the valve head 19 with some lift loss in the valve stem 1, and attendant noise, but still sufficient to enable operation of the engine.

Operation of the device will be very brief inasmuch as it is believed well known in this art from the prior patent cited and wide usage heretofore. Suffice it to say, rotation of the cam moves the tappet body and the compensating mechanism therein upwardly and upon reaching the base circle of the cam, in downward movement, during the dwell portion thereof, the plunger spring 22 is momentarily freed of the valve gear load to move the plunger 21 outwardly and induct a charge of oil upwardly from the reservoir through hollow tubular valve element 18 and around valve portion 19 into the space below the plunger where the oil is trapped by the valve seating immediately thereafter, as the load of the valve gear is picked up by upward movement of the tappet body under the cam action. The oil being incompressible the valve gear thus rides on a solid hydraulic column to maintain a noiseless zero clearance contact with the valve stem 1. Provision for expansion of the length of the valve gear parts under normal operating temperatures is accommodated by predetermined fluid escapement upward around the sides of the plunger by a selective fit with its cylinder 16, and the oil so eliminated will be replaced as the cycle of operation is repeated, all as previously described in the aforementioned patent.

Difficulty has been experienced in honing the bore of the separate cylinder 16, such as found in the mentioned Voorhies patent, with sufficient accuracy in production machining, due to its blind bore. As previously stated the fit of the plunger 21 in the separate cylinder 16 should be close and accurate to afford a predetermined fluid escapement and not such as to afford little reduction in the hydraulic column during the pressure interval between the valve stem and the tappet. Also in the previous structures pressing in of the oil suction tube and valve cage assembly if not accurately machined and assembled tended to distort the concentricity of the separate cylinder bore and this inaccuracy was reflected in the fit of the plunger when inserted therein.

In the present application these difficulties have been avoided and the problem solved by provision of the separate open ended cylinder 16 which may be readily formed from stock material and easily and accurately machined inasmuch as

a hone may be passed completely through it which thus eliminates the disadvantages heretofore encountered in attempting to hone a blind bore. The valve retaining blank 15 is likewise separately and easily formed and machined and the parts assembled together with a minimum of selective fits. Fluid escapement, if any, from the compression chamber outward between the juncture of the cylinder and valve retaining member 15 is prevented by the sealing washer 17, aforementioned, or any of the sealing means shown in other figures of the drawing. Although the bottom of the cylinder 16, which comprises the valve retainer 15 in this case, is formed separate from the cylinder 16 and not permanently secured thereto, as long as no leakage is permitted at the joint between these two parts the structure will operate satisfactorily. This is for the reason that the cylinder 16 will always be held in operative relationship with respect to the retainer 15 through pressure of the spring 22 so that while the retainer 15 may be readily removed from the cylinder 16 upon disassembly as long as the seal 17 seals the joint between them, fit between the two is not important. On the other hand it will be appreciated, of course, that the retainer 15 may have a light press fit into the cylinder 16 if this is deemed to be of advantage.

In Fig. 2 a very similar construction is shown in which a modified sealing washer 17a is inserted in a peripheral groove of the valve retaining element 15a for positive sealing of the juncture thereof with the separate cylinder 16. In this instance the poppet valve portion 19, of the tubular element 18, is also an angular valve seating surface cooperating with a complementary portion of the valve retaining element. Otherwise all the features, attendant advantages and operating principles of the previous construction are embodied in this modified structure.

In Fig. 3 another modification is shown also very similar to the first construction, but in this instance the sealing washer 17 previously described has been replaced by a washer element 17b which provides a combination sealing means for the juncture of the separate cylinder 16 with valve retaining element 15b, and also a portion of the seating surface of the valve element 19a therewith, that is flat seated as distinguished from angular seat 19.

Another modification shown in Fig. 3 and which is applicable to any of the other constructions shown is that instead of employing a snap ring such as 20 to limit upward movement of the tubular element 18a and valve 19a a spring may be employed in its place to obtain the same and an additional result. In this connection, in the particular embodiment shown in Fig. 3 the tubular element 18a is circumferentially cut away or grooved to form an axially disposed shoulder 23 upon which seats the lower end of a cone type of coil spring 24, the spring 24 being normally held under a light tension between the seat 23 and the bottom of the valve retaining element 15b. This form of construction not only serves the same purpose as the snap ring 20 in limiting upward movement of the valve 19a but further aids in increasing the speed of action of the valve and for this reason it may adapt itself for use in tappets employed on higher speed engines than the type of construction shown in the remaining views. Otherwise this construction functions in the same manner and with the attendant advantages of the device in Fig. 1.

In Figs. 4 and 5 the location of further modified

sealing washers 17c and 17d, respectively, together with their respective valve portions 19b and 19c, have been varied as shown to illustrate optional constructions that may be employed. In these instances the sealing washer is either imbedded in the seating surface of the valve as by being received in an annular groove as shown in the case of the valve portion 19b in Fig. 4, or carried thereby in a peripheral groove, as shown in the case of the valve portion 19c in Fig. 5, as distinguished from the previous structures wherein it was supported by the valve retaining elements 15, 15a or 15b.

In Fig. 6 a further modified tappet construction is shown embodying the idea of a separate open ended cylinder 16, as in the previous instances, and the sealing washer 17, and valve retaining element 15c, but incorporating a one-way check valve construction similar to that shown in the prior art above identified. A hollow tubular element 18a has a headed portion providing a valve seat which is press fitted into the member 15c. A ball type check valve 25 is seated thereon and surrounded by a ball cage member 26 which is press fitted into the valve retaining element 15c to provide a predetermined opening travel for the check valve. In this instance the hollow tubular element is, of course, not slidably mounted as in the previous instances since the valve means is incorporated in the movable ball check on the upper end thereof.

Formal changes may be made in the specific embodiments of the invention described without departing from the spirit or substance of the broad invention, the scope of which is commensurate with the following claims.

What I claim is:

1. A hydraulic valve tappet comprising a tappet body having a longitudinal bore closed at its lower end and adapted to receive a liquid, an apertured valve seat member supported in said bore, a separate open ended cylinder seated upon said valve seat member, a hollow tubular element extended from the lower part of the valve seat member into the closed end of the bore, one-way valve means at the upper end of said tubular element adapted to allow liquid to flow upwardly from the closed end of the bore into the cylinder, a plunger slidably mounted in the cylinder and biased outwardly therefrom, and means for maintaining liquid in the bore.

2. A hydraulic valve tappet comprising a tappet body having a longitudinal bore closed at its lower end and adapted to receive a liquid, an apertured valve seat member supported in said bore, a separate open ended cylinder seated upon said valve seat member, means for sealing the juncture of the lower end of the separate cylinder and the valve seat member, a hollow tubular element extended from the lower part of the valve seat member into the closed end of the bore, a one-way valve means at the upper end of said tubular element adapted to allow liquid to flow upwardly from the closed end of the bore into the cylinder, a plunger slidably mounted in the cylinder and biased outwardly therefrom, and means for maintaining liquid in the bore.

3. A hydraulic valve tappet comprising a tappet body having a longitudinal bore closed at its lower end and adapted to receive a liquid, an apertured valve seat member supported in said bore, a separate open ended cylinder disposed within said bore and seated upon said valve seat member, a hollow tubular element extended from the lower part of the valve seat member into the closed

end of the bore and including a one-way valve means on the upper end thereof adapted to allow liquid to flow upwardly from the closed end of the bore into the cylinder, combination means for sealing the juncture of the separate cylinder with the valve seat member and also for partially seating the one-way valve means thereof, a plunger slidably mounted in the cylinder and biased outwardly therefrom, and means for maintaining liquid in the bore.

4. A hydraulic valve tappet comprising a tappet body having a longitudinal bore closed at its lower end and adapted to receive a liquid, a separate open ended cylinder disposed in said bore, an apertured valve seat member supported in said bore and seating the lower end of the separate cylinder, a hollow tubular element slidably received by said valve seat member and extended from the lower part of the valve seat member into the closed end of the bore and including a one-way valve means on the upper end thereof adapted to allow liquid to flow upwardly from the closed end of the bore into the cylinder, means for limiting said sliding movement of the one-way valve means relative to said valve seat member, a plunger slidably mounted in the cylinder and biased outwardly therefrom, and means for maintaining liquid in the bore.

5. A hydraulic valve tappet comprising a tappet body having a longitudinal bore closed at its lower end and adapted to receive a liquid, a separate open ended cylinder disposed in said bore, an apertured valve seat member supported in said bore and seating the lower end of the separate cylinder, a hollow tubular element slidably received by said valve seat member and extended from the lower part of the valve seat member into the closed end of the bore and including a one-way valve means on the upper end thereof adapted to allow liquid to flow upwardly from the closed end of the bore into the cylinder, means for limiting said sliding movement of the one-way valve means relative to said valve seat member, combination means for sealing the juncture of the separate cylinder with the valve retaining member and also for seating the one-way valve means thereof, a plunger slidably mounted in the cylinder and biased outwardly therefrom, and means for maintaining liquid in the bore.

6. A hydraulic valve tappet comprising a tappet body having a longitudinal bore closed at its lower end and adapted to receive a liquid, a separate open ended cylinder disposed in said bore, an apertured valve retaining member supported in said bore and seating the lower end of the separate cylinder, a hollow tubular element slidably received by said valve retaining member and extended from the lower part of the valve retaining member into the closed end of the bore and including a one-way valve means on the upper end thereof adapted to allow liquid to flow upwardly from the closed end of the bore into the cylinder, snap ring means extended around the tubular element and arranged to abut against the lower end of the valve retaining member for limiting movement of the one way valve means of the tubular element to a predetermined amount, a plunger slidably mounted in the cylinder and biased outwardly therefrom, and means for maintaining liquid in the bore.

7. A hydraulic valve tappet comprising a tappet body having a longitudinal bore closed at its lower end and adapted to receive a liquid, a separate open ended cylinder disposed in said bore, an apertured valve retaining member supported in

said bore and seating the lower end of the separate cylinder, a hollow tubular element slidably received by said valve retaining member and extended from the lower part of the valve retaining member into the closed end of the bore and including a one-way valve means on the upper end thereof adapted to allow liquid to flow upwardly from the closed end of the bore into the cylinder, spring means constantly urging said valve means toward seated position, a plunger slidably mounted in the cylinder and biased outwardly therefrom, and means for maintaining liquid in the bore.

8. A hydraulic valve tappet comprising a tappet body having a longitudinal bore closed at its lower end and adapted to receive a liquid, a separate open ended cylinder disposed in said bore, an apertured valve retaining member supported in said bore and seating the lower end of the separate cylinder, a hollow tubular element slidably received by said valve retaining member and extended from the lower part of the valve retaining member into the closed end of the bore and including a poppet valve means on the upper end thereof adapted to allow liquid to flow upwardly from the closed end of the bore into the cylinder, means for limiting movement of the poppet valve means of the tubular element, seating means for said poppet valve on the valve retaining member, a plunger slidably mounted in the cylinder and biased outwardly therefrom, and means for maintaining liquid in the bore.

9. A hydraulic valve tappet comprising a tappet body having a longitudinal bore closed at its lower end and adapted to receive a liquid, a separate open ended cylinder disposed in said bore, an apertured valve retaining member supported in said bore and seating the lower end of the separate cylinder, a hollow tubular element slidably received by said valve retaining member and extended from the lower part of the valve retaining member into the closed end of the bore and including a poppet valve means on the upper end thereof adapted to allow liquid to flow upwardly from the closed end of the bore into the cylinder, means for limiting movement of the poppet valve means relative to said valve retaining member, seating means for said poppet valve on the valve retaining member, combination means for sealing the juncture of the separate cylinder with the valve retaining member and also for partially sealing the poppet valve means thereof, a plunger slidably mounted in the cylinder and biased outwardly therefrom, and means for maintaining liquid in the bore.

10. A hydraulic valve tappet comprising a tappet body having a longitudinal bore closed at its lower end and adapted to receive a liquid, a separate open ended cylinder disposed in said bore, an apertured valve retaining member supported in said bore and seating the lower end of the separate cylinder, a hollow tubular element slidably received by said valve retaining member and extended from the lower part of the valve retaining member into the closed end of the bore and including a poppet valve means on the upper end thereof adapted to allow liquid to flow upwardly from the closed end of the bore into the cylinder, means for limiting movement of the poppet valve

means relative to said valve retaining member, seating means for said poppet valve on the valve retaining member, yieldable means imbedded in a seating surface of the poppet valve for sealing the same to said valve retaining member when in a closed position, a plunger slidably mounted in the cylinder and biased outwardly therefrom, and means for maintaining liquid in the bore.

11. A hydraulic valve tappet comprising a tappet body having a longitudinal bore closed at its lower end and adapted to receive a liquid, a separate open ended cylinder disposed in said bore, an apertured valve retaining member supported in said bore and seating the lower end of the separate cylinder, a hollow tubular element slidably received by said valve retaining member and extended from the lower part of the valve retaining member into the closed end of the bore and including a poppet valve means on the upper end thereof adapted to allow liquid to flow upwardly from the closed end of the bore into the cylinder, means for limiting movement of the poppet valve means of the tubular element, seating means for said poppet valve on the valve retaining member, yieldable means carried by a seating surface of the poppet valve for sealing the same to said valve retaining member when in a closed position, a plunger slidably mounted in the cylinder and biased outwardly therefrom, and means for maintaining liquid in the bore.

12. A hydraulic valve tappet comprising a tappet body having a longitudinal bore closed at its lower end and adapted to receive a liquid, a separate open ended cylinder disposed in said bore, an apertured valve retaining member supported in said bore and seating the lower end of the separate cylinder, a hollow tubular element slidably received by said valve retaining member and extended from the lower part of the valve retaining member into the closed end of the bore and including a poppet valve means on the upper end thereof adapted to allow liquid to flow upwardly from the closed end of the bore into the cylinder, means for limiting movement of the poppet valve means of the tubular element to a predetermined amount, seating means for said poppet valve on the valve retaining member, means supported by the valve retaining member providing a combination yieldable seal with the poppet valve and also the juncture with the separate cylinder, a plunger slidably mounted in the cylinder and biased outwardly therefrom, and means for maintaining liquid in the bore.

13. A hydraulic valve tappet comprising a tappet body having a longitudinal bore closed at its lower end and adapted to receive a liquid, a separate cylinder disposed in said bore, a hollow tubular element slidably mounted relative to said cylinder extended from the lower part of the cylinder into the bore and including a one-way valve means on the upper end thereof adapted to allow liquid to flow upwardly from the lower part of the bore into the cylinder, means for limiting opening movement of the one-way valve means of the tubular element to a predetermined amount, a plunger slidably mounted in the cylinder and biased outwardly therefrom, and means for maintaining liquid in the bore.

HARRY E. VOORHIES.
